RESCUE CAR

Application filed February 20, 1928. Serial No. 255,683.

This invention relates to a device adapted for use with submarine boats, and more particularly to what I term a rescue car.

Great difficulty is experienced in rescuing 5 men from a submarine boat which is submerged at an appreciable depth and, due to injury or other causes, is unable to rise to the surface. Under such conditions the men cannot safely escape through the access hatches 10 or by means of the torpedo tubes, as can be done in shallow water, since the high pressure at greater depths is injurious and, in many cases, fatal to men exposed to such pressure. Under such conditions, even though a man 15 were not drowned before reaching the surface his chances of rescue are very slight. I have found that these difficulties can be avoided by providing a suitable container or car, which is adapted to withstand the high pres- 20 sure encountered at the greater depths in which a submarine boat may be submerged, this car being adapted for insertion into the torpedo tubes of the boat and having means for effecting a watertight closure with the 25 muzzle end of the tube, a suitable removable closure being provided for the inner end of the car when inserted into the tube. This renders it possible to insert the car into a tor- 30pedo tube after which the tube is drained and the removable cover is removed from the inner end of the car so as to permit the men to be rescued to enter the car, after which the removable cover or closure for the car is re- 35placed and the car is then removed from the tube and raised to the surface. In this manner rescue of the men can be effected without subjecting them to the high pressures obtain- 40ing at appreciable depths. Further objects and advantages of my invention will appear from the detail description.

In the drawings:

Fig. 1 is an elevation, partly broken away and in section, of a rescue car constructed in accordance with my invention as used with a 45 torpedo tube of known type, the torpedo tube and associated parts being shown in section;

Fig. 2 is a section taken substantially on line 2-2 of Fig. 1;

Fig. 3 is a fragmentary section taken sub- 50stantially on line 3-3 of Fig. 2, this section

being taken through the rescue car only and the torpedo tube and associated parts being omitted;

Fig. 4 is an inner end view of the car showing a modified form of closure means applied thereto; 55

Fig. 5 is a section taken substantially on line 5-5 of Fig. 4;

Fig. 6 is a fragmentary section through the inner end portion of the torpedo tube and the 60 car, showing a second modified form of closure for the inner end of the car; 60

Fig. 7 is a semi-diagrammatic view illustrating the method of lowering the car and inserting it into the torpedo tube. 65

In accordance with my invention, I construct a cylindrical container or body 1 which is formed of sheet steel or other suitable material and possesses sufficient strength to resist the high pressures which obtain at a depth of several hundred feet or more. At one end the body 1 is closed by a rounded head 2 having a flange 3 which fits tightly into the end of the body and is secured therein by welding or in any other suitable manner 70 to form a watertight closure therewith. This head is provided with an outer annular flange 4 having a dovetail recess for reception of a packing member or gasket 5 disposed to seat against the beaded outer or muzzle end 75 of a torpedo tube 6 of known construction. The body 1 of the car is of appreciably smaller diameter than the interior of the tube 6 to facilitate insertion of the car into the tube. The head 2 is further provided with an eye 80 member 7 secured thereto by riveting or in any other suitable manner, this eye member being adapted for reception of a cable or line 85 from a surface ship for lowering and raising the car. 90

A ring member 8 is secured in the other end of body 1 by welding, or in any other suitable manner, to form a watertight closure therewith. This ring member defines an opening which is normally closed by a cover 95 or door 9 of rounded shape which is hinged at 10 to the ring member. This door is provided with a thickened peripheral portion having a dovetail groove which receives a packing member or gasket 11 which seats 100

against the end of the ring member and forms a watertight closure therewith when the door is in closed position. Suitable dogs 12 are provided on the door and engage co-operating abutment members 13 secured on the inner face of ring 8. The dogs 12 and members 13 cooperate to secure the door 9 closed and to force the gasket 11 tightly against the end of ring 8. The dogs 12 are of known type, and each comprises an outer handle 12^a, an inner cam member 12^b which is preferably elongated to provide a handle for operating the dog from within the car, and a connecting rod or spindle 12^c passing through cover 9, the handle 12^a and member 12^b being suitably secured on the ends of spindle 12^c. Cam member 12^b has a camming action with the abutment member or lug 13 and coacts therewith for forcing the cover tightly closed and securing it. Dogs of this type for securing hatch scuttles or covers are known, and their operation is well understood by those skilled in the art. The dogs are constructed to be operated either interiorly or exteriorly of the body 1, as will be clear from Fig. 3 of the drawings.

A pane or block 14 of glass or other suitable transparent material is secured in cover 2 in a suitable manner and permits the diver 30 to see into the container 1 at the outer end thereof when the container is inserted into the tube 6. A target 15 of suitable type is mounted on an operating rod 16 which is slidable through guides 17 secured to the inner face of body 1 and ring 8. This rod also passes through a bracket 18 secured to the inner face of the body and is urged toward the door 9 by an expansion coil spring 19 mounted about the rod and confined between bracket 18 and a collar 20 secured on the rod. Movement of the rod toward the door is limited by a stop pin 21 secured therein and disposed to contact with the guide member 17 secured on the inner face of ring 8. The target 15 may be of any suitable type, that used being preferably a luminous type target such as will be readily visible through the glass 14 when disposed closely adjacent the inner face thereof but not readily visible 50 when withdrawn from the glass. The other end of rod 16 is disposed to contact with door 9 adjacent the periphery thereof when the door is closed. Closing of the door moves the rod 16 towards the opposite end of the body 1 so as to dispose the target 15 closely adjacent the glass pane 14. This provides simple and efficient indicating means for signaling to the diver exterior of the submarine boat when the door 9 is closed.

60 The car constructed in the manner illustrated and described is adapted for use with the torpedo tube 6 of a submarine boat of known construction the inner and outer hulls 22 and 23, respectively, of which are shown 65 fragmentarily and in section in Fig. 1 of the

drawings. The car is preferably of a length corresponding approximately to the length of the tube 6 so that when fully inserted into the tube the door 9 is disposed closely adjacent the breech door 10 of the tube. The tube has associated therewith means for flooding and draining the tube and means for opening and closing the muzzle door 11. Such means are common to the art and well understood by those acquainted with submarine boats, and need not be illustrated nor described in detail.

In using my rescue car, after locating the torpedo tube of the disabled submarine the diver signals to the occupants thereof who thereupon flood the tube 6, the muzzle cover 11 being in its normal closed position. After the tube has been flooded the cover 11 is opened in a known manner and the diver or divers insert the car into tube 6 so as to bring the flange 4 against the beaded muzzle end of the tube. The occupants of the compartment of the submarine boat are then advised that the rescue car is in position and drain the tube 6, the pressure on head 2 serving to hold the flange 4 thereof tightly against the muzzle end of the tube and to force the gasket 5 into watertight contact with the tube. After the tube has been drained, the breech door 10 thereof is removed. The dogs 12 are then turned to release door 9 of the car and two of the occupants of the compartment enter the car, the second occupant entering feet first so that the occupants are disposed with their feet adjacent each other and their heads toward the ends of the car, as illustrated in Fig. 1. The door 9 of the car is then closed and secured by the remaining occupants of the compartment of the submarine, after which the breech door 10 of tube 6 is replaced and, after signaling to the divers, the torpedo tube is flooded to permit withdrawal of the car. The car is then raised to the surface by means of a cable or line passed through the eye member 7 and the occupants are removed therefrom, after which the door 9 is closed and the car is returned to the divers. When the car is withdrawn from the tube 6 the muzzle cover may be left open and upon return of the car to the divers it is again inserted into the torpedo tube, the operation above described being repeated. In the case of the last man leaving the compartment of the submarine, the breech door 10 of the tube 6 is secured open in any suitable manner and the compartment of the submarine is flooded. This may be accomplished by opening a valve within the compartment or means operable by the diver exterior of the boat may be provided for effecting flooding of the compartment. When the incoming water causes the pressure inside of the compartment to equal that on the outside the rescue car may be withdrawn and raised to the surface in the manner described.

In the modified form of closure for the access end of the car 1, illustrated in Figs. 4 and 5, a ring 24 is secured in the end of body 1 by being welded therein, or in any other suitable manner. The inner face of this ring is beveled at 25 to avoid a projection or sharp edge which might injure the man in the lower portion of the car during raising thereof. The ring 24 is provided with a rabbet in its outer portion which receives a packing ring or gasket 26 which cooperates with flange 27^a of a door or closure member 27. The closure member 27 is provided with an inwardly extending flange 28 of a diameter to fit snugly within ring 24. Securing pins 29 are secured in the flange 28 and disposed to engage into bayonet slots 30 extending from the outer edge of ring 24. The flange 28 is further provided with two integral bosses 31 which receive the ends of a cross bar 32. This cross bar forms a hand hold by means of which the occupant of the inner end or portion of the car is enabled to tightly secure the closure member 27 in closed position before withdrawal of the car from the torpedo tube. This is, of course, essential in the case of the last man leaving the compartment of the submarine. The form illustrated in Fig. 6 is similar to that of Figs. 4 and 5 except that the flange 28^a of the cover member is exteriorly threaded and screws into the ring 24^a which is interiorly threaded.

While the form of closure for the access end of the car illustrated in Figs. 1 to 3, is efficient and satisfactory when the car is used with the larger size of torpedo tube, which has a diameter of 21 inches, I find that for the smaller size tube having a diameter of 18 inches, the closures illustrated in Figs. 4 to 6, are preferable as the closure members 27 can be removed in such manner as to leave practically the entire end of the car open and unobstructed for ingress and egress.

To facilitate insertion and removal of the closure member 27, this member is provided, on its outer face with a plurality of ribs 33 which are disposed radially of the member 27 and are equally spaced. I have shown four of these ribs, though the number of ribs employed may vary, as desired. Each of the ribs is provided with a hand opening 34, the ribs thus forming hand holds which facilitate turning of the cover 27 to screw the same into or out of the end of the car. The ribs 33 are arcuate and decrease uniformly in width from the center of the cover to the periphery thereof, as illustrated in Figs. 5 and 6. The two pairs of ribs disposed at right angles to each other thus provide, in effect, a rounded surface which eliminates undesirable projections, such as might interfere with manipulation of the car when inserting it into or removing it from the torpedo tube.

In order that the car may be readily manip-

ulated by the divers, a suitable ballast member 35 is secured within body 1 in a suitable manner, this member being disposed equidistant from the ends of the car. The ballast member is of proper weight to impart a slight negative buoyancy to the car and is so disposed as to cause the car to tend to assume a horizontal position in the water. This facilitates manipulation of the car and insertion thereof into the torpedo tube. While the car may be handled by one diver at the disabled submarine, I preferably have two divers to handle the car due to its length and in order that the men in the compartment of the submarine boat may be removed therefrom as expeditiously as possible.

The car is preferably lowered in horizontal position and suspended adjacent and in alignment with the torpedo tube so as to be readily inserted thereinto upon opening of the muzzle cover. To accomplish this I provide a suitable bridle 35' (Fig. 7) secured to a line 36 by which the car is raised and lowered, this line being secured through eye 7. The bridle is secured about the car at opposite sides of and equidistant from the centre thereof, thus supporting the car horizontally as it is lowered into position. When the muzzle cover 11 is opened, the car is inserted into the torpedo tube a short distance. The bridle is then removed, after which the car is inserted into its full operative position within the tube. This greatly facilitates handling of the car and insertion thereof into the torpedo tube.

While I have shown a removable closure or door at one end of the car, I contemplate providing removable closures at both ends of the car, as in my copending application for rescue submarine filed February 20, 1928, Serial Number 255,684. This is advantageous as facilitating escape or removal of the occupants from the car.

What I claim is:—

1. In a rescue car for use with submarine boats, a hollow body closed at one end and adapted for insertion into a torpedo tube, the body being provided at said end with means for effecting a water tight closure with the muzzle end of the tube, a removable water tight closure for the other end of the body, and signal means effective at the first mentioned end of the body and actuated by the closure for indicating when said closure is in position to close said other end of the body.

2. In a rescue car for use with submarine boats, a hollow body closed at one end and adapted for insertion into a tubular member opening through the hull of the boat, the body being provided at said end with means for effecting a water tight closure with the adjacent end of said member, a removable water tight closure for the other end of the body, and signal means effective at the first

mentioned end of the body and actuated by the closure for indicating when said closure is in position to close said other end of the body.

5 In witness whereof, I have hereunto subscribed my name this 2nd day of February, 1928.

LAWRENCE Y. SPEAR.
